DESIGN FOR A KEY CASE

John J. Calichio, New York, N. Y.

Application February 6, 1941, Serial No. 98,804

Term of patent 7 years

To all whom it may concern:

Be it known that I, John J. Calichio, a citizen of the United States, residing in the city of New York, county of Queens, State of New York, have invented a new, original, and ornamental Design for a Key Case, of which the following is a specification, reference being had to the accompanying drawing, forming part thereof.

Fig. 1 is a perspective view of a key case embodying my new design;

Fig. 2 is a top plan view thereof;
Fig. 3 is a front end elevational view thereof;
and

Fig. 4 is a rear end elevational view thereof.

I claim:

The ornamental design for a key case, substantially as shown.

JOHN J. CALICHIO,
